UNITED STATES PATENT OFFICE

2,154,899

FEED DRUM FOR SNAP FASTENER SETTERS

Julius Gualtieri, Brooklyn, N. Y., assignor to Edwin B. Stimpson Company, Brooklyn, N. Y., a corporation of New York

Original application May 16, 1934, Serial No. 725,888. Divided and this application January 27, 1936, Serial No. 60,994

1 Claim. (Cl. 218—2.1)

The present invention relates to drums for feeding elements of snap fasteners in a snap fastener setting machine and comprises a division of Gualtieri application Serial No. 725,888, filed May 16, 1934, now Patent No. 2,061,193, granted November 17, 1936.

Snap fasteners usually comprise two members, namely, a snap socket which passes through the material and a cap on the other side of the material into which the socket is expanded to anchor the cap in place and to hold the socket securely riveted in place in the material. Snap fasteners of this kind are common as glove snaps and as many other articles of commerce.

Heretofore in the art, it has been customary to feed the parts by hand to a rivet setter which was adapted to apply pressure to expand the socket within the cap and hold the parts securely locked in place.

The present invention comprises feed drums for an automatic machine which for each operation of the machine automatically feeds a socket member and a fastener cap and then applies pressure to expand the fastener within the cap.

The cycle of operations of the machine is such that a socket is positioned at the work anvil. The goods, having an opening perforated therein to receive the stem of the fastener, is slipped over the socket and the machine is then operated.

The operation of the machine feeds a cap over the portion of the socket extending through the goods, and applies pressure to expand the stem of the socket within the cap. It, therefore, will be seen that each operation of the machine results in a completed fastener comprising a socket and a cap being automatically applied to the goods.

The feed drums of the machine comprise novel constructions for feeding both the caps and the sockets. The sockets are small hollow stemmed tubular members shaped somewhat like a head gear known as a "stove pipe" hat. The feed mechanism for the sockets comprises a feed drum and a feed ring spaced slightly from the face of the drum, so that the socket members leave the feed drum with the stems passing through exit slots in the feed ring. The stems of the sockets extend inwardly toward the machine. This is the opposite position usually provided for feeding articles of this shape and the reversal of the feed position is due to the novel feed ring spaced from the face of the feed drum.

The caps comprise hollow members being rounded or oval on one side and provided with an opening on the other side. The feed passageways provided in the edge of the feed drum for

the caps are constructed with conical projections located in the central part of each feed passageway. The facing adjacent the cap feed drum is provided with an annular groove opposite the path of the said projections. A cap falling into a passageway with the back of the cap toward the outer face of the feed drum will be blocked from going through the passageway by the conical projection, but any cap falling into a passageway with the back of the cap toward the facing will slide downward through the passageway and the conical projection will pass into the opening in the cap and gravity will cause the cap to slide over the face of the conical projection and out into a feed channel. This arrangement permits the feed of the caps in such manner that all of the tops of the caps face in one direction in the cap runway so that the caps come right side up into proper place for further operations.

It is realized that the invention may be practiced by constructions other than those specifically illustrated herewith, so, therefore, the specific disclosure herewith is to be understood as illustrative and not in the limiting sense.

Fig. 1 is a view showing a side elevation of the machine with certain portions broken away to illustrate interior constructions.

Fig. 2 is a front elevational view showing certain parts in section.

Fig. 3 is a sectional view of a portion of the rim and attached ring of the socket feeding drum.

Fig. 4 is a detail view of a portion of the face in the socket feeding drum on line 4—4 of Fig. 3.

Fig. 5 is an elevational edge view of the feed ring adapted to be attached to the feed drum 35 illustrated in Figs. 3 and 4 and showing a portion of the ring broken away.

Fig. 6 is a front view of the face of the ring shown in Fig. 5.

Fig. 7 is a detail view illustrating a portion of 40 the rotating feed drum for feeding the caps.

Fig. 8 is a front face view of the feed drum shown in Fig. 6.

Referring to the drawings and more especially to Fig. 1, a pedestal frame 1 carries an electric motor 2 which is the driving unit for the device. An operating pedal 4 is pivoted in the base of the pedestal frame and is normally held in raised position by a coil spring 5 anchored at one end to the pedestal frame and at the other end to the 50 pedal. An adjustable stop 6 limits the upward movement of the pedal. A head frame 7 is securely mounted on the pedestal frame 1 and is the main support for the operating mechanism. The electric motor 2 is connected by a belt 8 with 55

a weighted drive pulley 9 to rotate the pulley in the direction of the arrow A (Fig. 1). A clutch link 10 extends from the pedal 4 to the clutch mechanism whereby the operator upon depressing the pedal 4 causes the clutch mechanism to engage the driving pulley 9 with the operating mechanism.

The upper part of the head frame 7 carries a pair of feed drums. One of these feed drums 10 feeds the socket members in a proper upright position and the other of the feed drums feeds the cap members properly positioned. Socket feed drum 62 (Fig. 2) feeds the socket members. The socket members are fed into this feed drum 15 from a feed hopper 64. This drum 62 is removably mounted upon a socket drum shaft and is intermittently rotated by a ratchet 66 which is fixedly mounted on the shaft as is well known in the art. This ratchet is intermittently operated 20 by a thrust dog 67 (Fig. 2). This thrust dog 67 is mounted on an arm 68 fixedly secured to oscillate with a short shaft to which the main lever 37 is anchored by an anchor stud, so that each time the main lever 37 is oscillated, the thrust 25 dog 67 engages and pushes forward the notches of the ratchet 66, as is shown in my Patent No. 2,061,193, November 17, 1936. As the feed drum 62 is intermittently rotated, socket members within this feed drum are tumbled about and 30 tend to slide toward the face of the drum.

In order that the socket members may be properly positioned for further operations, it is necessary that the stems of the socket members shall be fed in an outward position relative to the 35 rim of the drum 62. This desirable and necessary operation is accomplished by the utilization of an auxiliary member comprising a ring (Figs. 3, 4, 5 and 6) mounted upon the face edge of the drum 62. The face of the drum 62 is provided with 40 guide grooves 70. These guide grooves lead to escape exits 71 for the socket members. These escape exits are in the separate ring 72 which is detachably mounted upon the face edge of the feed drum 62 by means of machine screws 80 which extend through the openings 81 in the ring 45 72. The ring 72 is also positioned on the feed drum 62 by means of dowel pins 82 that are carried by the ring 72 and extend into openings 83 in the feed drum 62. By this construction, it 50 will be observed that the socket members 74 can only escape from the feed drum 62 with the stems of the socket members extending toward the central axis of the machine frame. The socket members, after escaping from the drum 62, slide down a runway 75 (Figs. 1 and 2).

The feed mechanism for the cap comprises a cap feed drum 111 (Figs. 1 and 2) which is removably mounted on a drum shaft 112 that rotates in a bearing 114 in the head frame 7. The inner end of this shaft 112 carries a feed ratchet 115 which is engaged by a pull ratchet pawl 116. This ratchet pawl 116 is mounted on an arm 117 fixedly secured to the shaft for the main lever 37. As the main lever 37 oscillates, the arm 117 swings to cause the ratchet pawl 116 to engage the ratchet 115 and rotate the drum shaft 112 step by step. The rotation of the drum shaft causes caps

fed into the drum 111 by the hopper 118 to be tumbled about in the cap feed drum 111. The feeding edge of this drum 111 (Figs. 7 and 8) is provided with exit pathways 119. In the center of each pathway 119 is a conical projection 120 comprising the head of a stud set in the edge of the drum. A groove 121 is provided in the facing 122 opposite the path of the conical heads 120. Baffle plates 124 are also provided within the body of the drum 111 to loosen up the mass 10 of caps within the drum as the drum rotates. These caps 125 are oval on the top and are provided with an opening on the opposite side. The studs 120 present obstacles to the escape of caps having the tops thereof in contact with the studs, 15 but permit caps having the open sides toward the studs to slide over the studs into the groove 120 and then slide off the studs into the feed groove 126.

As the machine operates, a cap resting in the 20 cup 135 is directly over a socket on the holding pin 51 in the path of the descending setting head 48. The downward movement of the setting head 48 carries the cup bar 138 downward against the action of the coil spring 139 until the movement of the cup bar 138 is stopped by a stop 140. The continued descent of the plunger 48 causes the spring arms of the cup 135 to swing outwardly (Fig. 2) to release the cap when it is in position directly over the end of the socket on the socket 30 pin 51. The continued movement of the setting head 48 applies pressure to the positioned cap, thereby expanding the upper end of the socket member within the cap and locking the same in position therein so that the socket 74 is securely 35 locked within the cap 125 which is tightly seated against the material 141, thereby completing the operating cycle of the machine.

It will be observed that in the operation of the machine, a socket is fed from one side of the 40 machine to arrive at the anvil in an upright position where it is held by the socket pin in the center of the anvil, and that a cap is fed from the other side of the machine in an upright position with the opening of the cap downward so that 45 the cap is set down upon the upper end of the socket and the plunger continues its downward descent to apply pressure to crush or flatten the upper end of the socket and expand the same within the cap, thereby locking the parts together. 50

Having described my invention, I claim:

In a machine of the class described, a socket feeding device comprising a socket drum adapted to receive and tumble a mass of sockets, means to intermittently rotate said drum upon a substantially horizontal axis, a feed rim on said drum provided with guide grooves for flanges of said sockets, a feed ring detachably mounted on the face of said feed rim, said feed ring having passageways therein for the stems of sockets and wider passageways for the flanges of sockets, said wider passageways being aligned with the guide grooves, and constructed and arranged to permit sockets to escape from the feed drum with the stems thereof extending away from the face of said feed rim.

JULIUS GUALTIERE.
